(57) **CLAIM**

I claim the ornamental design for an automatic pet food dispenser, as shown and described.

DESCRIPTION

FIG. 1 is a perspective view of an automatic pet food dispenser;

FIG. 2 is a front view of the automatic pet food dispenser of FIG. 1;

FIG. 3 is a rear view of the automatic pet food dispenser of FIG. 1;

FIG. 4 is a left side view of the automatic pet food dispenser of FIG. 1;

FIG. 5 is a right side view of the automatic pet food dispenser of FIG. 1;

FIG. 6 is a top view of the automatic pet food dispenser of FIG. 1; and,

FIG. 7 is a bottom view of the automatic pet food dispenser of FIG. 1.

Broken lines and entirely unshaded portions contained within broken lines are not claimed.

1 Claim, 7 Drawing Sheets
